(57) CLAIM

The ornamental design for an x-ray shield, as shown and described.

DESCRIPTION

FIG. 1 is a front perspective view of the x-ray shield showing my new design;

FIG. 2 is a rear view thereof;

FIG. 3 is a left side view thereof, the right side view being a mirror image; and,

FIG. 4 is a top view thereof.

The broken lines represent environmental structure and are for illustrative purposes only. The broken lines form no part of the claimed design.

1 Claim, 4 Drawing Sheets(56)
